CLAIM

The ornamental design for a block set as shown and described.

DESCRIPTION

FIG. 1 is a perspective view of a first block of a block set showing the claimed design wherein the first block has the following angles; [(90,45,45), (90,35.3,54.7), (90,30,60), (90,35.3,54.7)]

FIG. 2 is front view of the first block;

FIG. 3 is a rear view of the first block;

FIG. 4 is a left side view of the first block;

FIG. 5 is a right side view of the first block;

FIG. 6 is a top view of the first block;

FIG. 7 is a bottom view of the first block;

FIG. 8 is a perspective view of a second block of a block set showing the claimed design wherein the second block has the following angles; [(90,45,45), (90,54.7,35.3), (90,60, 30), (90,54.7,35.3)]

FIG. 9 is front view of the second block;

FIG. 10 is a rear view of the second block;

FIG. 11 is a left side view of the second block;

FIG. 12 is a right side view of the second block;

FIG. 13 is a top view of the second block;

FIG. 14 is a bottom view of the second block;

FIG. 15 is a perspective view of a third block of a block set showing the claimed design wherein the third block has the following angles; [(90,54.7,35.3), (19.5,70.5,90), (30,60, 90), (90,54.7,35.3)]

FIG. 16 is front view of the third block;

FIG. 17 is a rear view of the third block;

FIG. 18 is a left side view of the third block;

FIG. 19 is a right side view of the third block;

FIG. 20 is a top view of the third block;

FIG. 21 is a bottom view of the third block;

FIG. 22 is a perspective view of a fourth block of a block set showing the claimed design wherein the fourth block has the following angles; [(90,35.3,54.7), (19.5,90,70.5), (30,90, 60), (90,35.3,54.7)]

FIG. 23 is front view of the fourth block;

FIG. 24 is a rear view of the fourth block;

FIG. 25 is a left side view of the fourth block;

FIG. 26 is a right side view of the fourth block;

FIG. 27 is a top view of the fourth block; and,

FIG. 28 is a bottom view of the fourth block.
